UNITED STATES PATENT OFFICE.

JOHN P. BUCKLEY, OF WASHINGTON, DISTRICT OF COLUMBIA.

MACHINE FOR COUNTING PAPER MONEY.

1,159,826.

Specification of Letters Patent.

Patented Nov. 9, 1915.

Application filed July 30, 1910. Serial No. 574,678.

To all whom it may concern:

Be it known that I, JOHN P. BUCKLEY, a citizen of the United States, residing at Washington, in the District of Columbia, 5 have invented new and useful Improvements in Machines for Counting Paper Money, of which the following is a specification.

This invention relates to an improved machine for use in counting paper money, and has for its main object the provision of means whereby the money, upon being fed to the machine, will be accurately counted.

A further object of the invention is to 15 provide means whereby, when a certain predetermined number of bills has been counted, the machine will come to rest, and the counting of any further bill or bills will be prevented until the machine is reset for 20 further operation.

A still further object of the invention is to provide means for keeping any particular package of money which has been counted separate and distinct from any other 25 package or bulk, whereby errors made in the original packaging or bundling may be readily traced.

The invention as embodied in one form is illustrated in the accompanying drawings, 30 wherein:

Figure 1 is a vertical longitudinal sectional view of the apparatus, taken on the line 1—1 of Fig. 4; Fig. 2 a transverse vertical sectional view, taken on the line 2—2 of Fig. 4, looking toward the forward portion 35 of the machine; Fig. 3 a similar view, taken on the line 3—3 of Fig. 4, looking forwardly; Fig. 4 a top plan view of the machine, portions being shown in section to 40 more clearly illustrate certain parts thereof; Fig. 5 a transverse vertical sectional view, taken on the line 5—5 of Fig. 4, illustrating the cut-out device for the electric circuit; Fig. 6 a sectional view, showing the parts 45 illustrated in Fig. 1, with a bill in position and the upper gates or supporting leaves elevated; Fig. 7 a transverse vertical sectional view, taken on the line 7—7 of Fig. 6, showing the gates or leaves in the same 50 relative positions as those which they occupy in Fig. 6; Fig. 8 a similar view, taken on the line 8—8 of Fig. 6, the parts being in the same relative positions; Fig. 9 a detail perspective view of the counter-actuating 55 pawl and its allied parts; and Fig. 10 a dia-

grammatic view showing the circuits employed in the machine.

In the drawings 1 denotes a base or stand surmounted by a housing open at the front and divided into two receptacles, 2 and 3, 60 by a pair of hinged gates or shelves 4 and 5, the former being secured at one edge to a rock-shaft 6, Fig. 2, while the latter is secured to a similar shaft 7. An arm or lever 8 is secured to the rearwardly-projecting 65 end of the shaft 6, the outer end of said lever being connected by a link 9 to a similar arm or lever 10, secured to the shaft 7. A hand lever 11 is also secured to the shaft 7, and by reason of the same, as will be 70 clearly apparent upon reference to Fig. 2, the gates or leaves 4 and 5 may be swung downwardly to discharge the counted bills which may be resting thereon into the receptacle 3. Normally the gates stand in the 75 position shown in Fig. 2, forming a false floor for the receptacle 2 upon which the bills, as they are counted, will be automatically stacked.

A similar pair of gates or hinged shelves 80 12 and 13 are mounted in the upper portion of the housing or framework, said shelves being shown in their lowered position in Figs. 1, 3 and 4, and in their elevated position in Figs. 6, 7 and 8. Gate 12 is secured 85 to and carried by a rock shaft 14, said shaft being provided at its rear end with an arm or lever 15, which latter is connected at its outer end by a link 16 to the outer end of a similar lever 17 secured upon a rock 90 shaft 18, which carries the gate 13. The gates are thus caused to open and close in unison each time the rock shaft 18 is oscillated. The shaft 18, as will be seen upon reference to Fig. 4, is extended rearwardly 95 of the main housing and passes through up-standing walls 19 and 20 of the supplemental housing or supporting member secured to the main frame in any suitable manner, as for instance by bolts and spacing collars 21, 100 Fig. 1.

The shaft 18 has secured to it a wheel-shaped member 22, the wheel being provided with a groove in which is seated and secured one end of a coiled spring 23, the 105 lower end of which is adjustably attached to a fixed portion of the machine. Normally this spring tends to rotate the wheel in the direction of the arrow in Fig. 2. Wheel 22 also has attached to one side face 110

thereof a link 24, the lower end of said link being pivotally attached to an armature 25, fulcrumed upon the supplemental frame, as at 26. The armature overlies the poles 5 of a magnet 27, said armature working in opposition to the spring, as will be herein-after more fully set forth, and serving to throw the gates or shelves 12 and 13 downwardly.

10 Pivoted to one side of wheel 22 is a pawl 28, adapted to coact with a toothed wheel 29, provided on its forward face with a series of graduations and numerals adapted to be exposed through an opening 30 formed 15 in the wall 19. The teeth of the wheel are spaced apart, there being an extra unindicated tooth between the first tooth and that designated "100." The reason for providing this extra tooth will presently appear.

20 Secured to the shaft 31, upon which the indicating disk or wheel 29 is mounted, is a disk or member 32, the shaft being mounted in insulated bushings, as is clearly shown in Fig. 6. Bearing upon the periphery of 25 said disk 32, which is spiral-like in form, is a contact brush 33. The disk is provided with an insulating section 34, located adjacent to the high point 35 upon the perimeter of the same, so that when the disk is 30 rotated and the brush 33 passes off the high point it will bear upon the insulated section and thus break the circuit in which the brush and disk are normally included.

Located at the forward upper portion of 35 the machine, in line with the uppermost gates or shelves, is a table or platform 36 upon which the bills to be counted are placed one by one by the operator or attendant. Between the inner end of the table and the 40 forward portion of the upper gates is a pair of rollers 37 and 38, said rollers being mounted in insulated bearings, one of them being driven through any suitable agency. Brushes 39 and 40 contact respectively with 45 the shafts of the feed rolls 37 and 38. Normally these rolls are in contact with each other and the circuit is completed, as will be seen upon reference to Figs. 4 and 10, through wire 41 leading to a source of current 42, a wire 43 leading to the magnet 27, thence to the brush 33, through disk 32, shaft 31, brush 44 (see Fig. 4) and wire 45 leading to the brush 39. The toothed wheel 29 will, of course, be insulated from 50 the shaft 31, so that the current will not be short-circuited through said wheel and the pawl to the frame of the machine.

55 A shunt connection 46, provided with a normally open switch 47, enables the operator to close the circuit directly through magnet 27 and to thus operate the pawl 28, so as to advance the wheel 29 the distance of one tooth.

Normally the circuit is closed by the contact of the rollers 37 and 38, at which time

the magnet is energized, its armature pulled down, and through its downward movement the wheel-shaped member 22 is partially rotated, and the shaft 18 is so moved as to throw the proximate inner edges of the 70 gates or shelves downwardly. This position is maintained until the operator presents a bill to the rotating roller, when its forward end will be grasped by the rollers and drawn inwardly between the same. 75 The moment this takes place the circuit is interrupted and the spring 23, acting through the member 22, levers 17 and 15, and the interposed link 16, causes the gates to swing upwardly in position to receive 80 the bill or note. The parts are so positioned that after the bill has passed inwardly between the rollers it will lie flat upon the gates and as this position is brought about the rolls come into contact 85 with each other and close the circuit, thereby energizing the magnet and bringing the parts to the positions first mentioned. The bill will then drop onto the lowermost gates, 4 and 5, where it will be supported. 90 This action continues until the brush 33 passes off of the high point 35 of the disk or member 32 and onto the circuit-breaking section 34.

95 Each time a bill passes from the rollers and the circuit is re-established or completed between them, the wheel-shaped member 22 will be moved in a direction the reverse of that indicated by the arrow in Fig. 2, and as a consequence the pawl 28 will be moved 100 and will advance the indicating wheel the distance of one tooth. When the circuit is again interrupted by the introduction of another bill, the spring 23 will move the wheel-shaped member 22 in the direction indicated by the arrow in Fig. 2, thus drawing the pawl downwardly the distance of one tooth and at the same time elevating the armature 25, carrying the parts to the positions shown in Fig. 7 where, upon the actuation of the armature by the completion of the circuit, the pawl 28 will again advance the indicating wheel. This operation will continue until the brush 33 contacts with the cut-out 34, as just mentioned, at 115 which time the counting mechanism will be locked and the upper gates held in their elevated position.

120 As will be readily appreciated, during this operation one hundred bills will have passed between the rollers and the counter will indicate the exact number thereof. No more bills can be counted until the disk 32 is moved so as to carry the insulating section 34 from beneath the end of the brush 125 33; consequently, the upper gates remain closed and it is impossible, even should bills be fed in between the rollers, to count the same and have them discharge onto the already-counted bills resting upon the gates 130

4 and 5. The operator can, therefore, discharge the stacked and counted bills from the compartment 2 by manipulating the lever 11 and causing the gates 4 and 5 to open and release the one hundred stacked bills into the receptacle 3, after which the lower gates will again be elevated to form a temporary platform for the upper compartment or chamber 2. When this has been accomplished and the operator desires to count additional bills, he closes the switch 47 and thereby energizes the magnet and causes the wheel-shaped member 22 to be actuated, thus advancing the indicating wheel 29 and the disk 32 one step, and carrying the insulating section 34 from beneath the end of the brush 33, reestablishing the parts in their normal operative positions, again ready to count upon the introduction of bills between the rollers 37 and 38.

In the use of the machine in counting money, particularly where the packages are banded and supposed to contain a given number of bills, as for instance one hundred, the operator can readily determine whether or not the package contains the right number, for if it contains only ninety-nine, for example, the indicator will register "99" and no more. The bills of the short package may then be removed from the machine and the matter rectified by inspection of the band, which usually contains an indicating mark or character that enables the proper authority to trace the package back to the party who banded the same. In such case it is, of course, necessary for the user of the machine to close the switch 47 twice, in order to first carry the brush 33 into operative relation with the cut-out 34 and thereafter out of position with relation to said cut-out.

Having thus described my invention, what I claim is:

1. In a machine for counting paper money, the combination of feeding means for the bills adapted to feed the same one at a time; a counter; an electric circuit adapted to be opened and closed by said feeding means; and operating means for the counter also included in the circuit.

2. In a machine for counting paper money, the combination of a counter; an electric circuit; operating means for the counter included in said circuit; and a feeding means for the bills, also included in the circuit, and adapted to interrupt the circuit while a bill is being fed by said means.

3. In a machine for counting paper money, the combination of a counter; an electric circuit; operating means for the counter included in the circuit; and feed rolls between which the bills to be counted are passed, one by one, said rolls controlling the passage of current through the circuit and consequently the actuation of the counter.

4. In a machine for counting paper money, the combination of a counter; an electric circuit; operating means for the counter included in the circuit; feeding means for the bills also included in the circuit and serving to make and break the same; and means for temporarily supporting a bill as it is advanced by said feeding means. 70

5. In a machine for counting paper money, the combination of a counter; an electric circuit; operating means for the counter included in the circuit; feeding means for the bills also included in the circuit and serving to make and break the same; a movable support for the bills adapted to receive and discharge the same one by one; and means collectively related with the counter-operating means for positioning said support. 75

6. In a machine for counting paper money, the combination of a counter; an electric circuit; means for actuating the counter included in the circuit; a pair of feed rolls also included in the circuit, said rolls serving to break the same when a bill is passed between them; a movable support located adjacent the discharge side of the rolls and adapted to receive a bill as it is discharged therefrom; and means for moving the support and discharging the deposited bill therefrom upon the completion of the feeding operation, said means also serving to actuate the counter. 80

7. In a machine for counting paper money, the combination of a movable support for the bills; means for advancing the bills one by one onto said support; a counter; and means for moving said support to discharge the deposited bill therefrom and to actuate the counter. 90

8. In a machine for counting paper money, the combination of a movable support for the bills; means for depositing the bills, one by one, upon said support; a counter; and means under the control of said depositing means for actuating the counter and moving said support to discharge the bill deposited thereon. 105

9. In a machine for counting paper money, the combination of a movable support for the bills; means for advancing the bills separately onto said support; means for actuating said support to discharge the bills therefrom; and a counter associated and operating in unison with said movable support. 115

10. In a machine for counting paper money, the combination of means for feeding or advancing the bills to be counted one by one; a pair of hinged shelves adapted to receive the bills from said feeding means; a counter; and means for swinging said shelves downwardly to discharge the deposited bill therefrom and likewise to actuate the counter. 120

11. In a machine for counting paper money, the combination of a pair of feed 125

- rolls adapted to advance the bills one by one; a pair of hinged shelves standing to one side of the rolls and adapted to receive a bill as it is discharged therefrom; a counter; and means for swinging said shelves downwardly to discharge the deposited bill and to actuate the counter.
12. In a machine for counting paper money, the combination of a pair of feed rolls adapted to advance the bills one by one; a pair of oppositely hinged shelves located in line with the discharge side of said rolls and adapted to receive the bill advanced therefrom; a counter; and means coöperating with said counter and the shelves to lower the latter and actuate the former when a bill has been deposited on said shelves.
13. In a machine for counting paper money, the combination of a pair of feed rolls; an electric circuit in which said rolls are included; a temporary support for the bills as they are advanced one by one between said rolls; a counter; an electro-magnet included in the circuit aforesaid; a pivoted armature associated with said magnet; and connections between said armature and the counter, and the armature and the support, whereby upon the passage of a bill from between the rolls the magnet will be energized, the support depressed, and the counter actuated.
14. In a machine for counting paper money, the combination of an electric circuit; a pair of feed rolls included in said circuit and normally closing the same; a support located adjacent said feed rolls and adapted to temporarily hold a bill as it is deposited thereon by the feed rolls; a counter; an electro-magnet included in the circuit aforesaid; an armature associated with said magnet; connections between said armature and the temporary support for the bills, and between said armature and the counter; and a cut-out for said circuit, adapted to be brought into operation when a predetermined number of bills have been counted.
15. In a machine for counting paper money, the combination of an electric circuit; a pair of feed rolls included in said circuit and normally closing the same; a support located adjacent said feed rolls and adapted to temporarily hold a bill as it is deposited thereon by the feed rolls; a counter; an electro-magnet included in the circuit aforesaid; an armature associated with said magnet; connections between said armature and the temporary support for the bills, and between said armature and the counter; and a cut-out for said circuit, adapted to be brought into operation when a predetermined number of bills have been counted.
16. In a machine for counting paper money, the combination of means for feeding bills one at a time; a temporary support adapted to receive such bills from the feeding means; a counter and means, controlled by the passage of a bill through the feeding means, for positioning the support, and controlling the actuation of the counter.
17. In a machine for counting paper money, the combination of two coacting members adapted to feed the bills to be counted, one at a time; a temporary supporting means adapted to be thrown up into position below the bill being fed; an electric circuit in which the feeding members are included and by which it is normally completed; a counter and means, also included in the circuit, for actuating said supporting means, and controlling the actuation of the counter.
18. In a machine for counting paper money, the combination of a pair of normally contacting feed rolls; an electric circuit in which said rolls are included; a counter; a movable support for the bills, arranged adjacent the discharge side of the rolls; and an electric magnet, included in the circuit, for actuating the counter and controlling the position of said movable support.
19. In a machine for counting paper money, the combination of a counter; a temporary support for the bills as they are counted; means for feeding the bills onto said support, one by one; and means for actuating the counter and moving the support to discharge the bills, one by one, as they are placed on said support.
